UNITED STATES PATENT OFFICE

JOSEPH L. TRESOUTHICK, OF JERSEY CITY, NEW JERSEY

WINDOW

Application filed May 12, 1931. Serial No. 536,857.

This invention relates to windows and has for an object to provide an improved construction wherein the sashes are resiliently held against rattling.

5 Another object of the invention is to provide an improved window wherein the sashes may be raised and lowered in the usual manner while being capable of being tilted when in a certain position.

10 A still further object of the invention is to provide a window of the usual appearance but formed so that the sashes are held against rattling and are provided with mountings which will permit the tilting of the sash while bringing the weather stripping associated therewith under tension for resiliently and frictionally holding the sashes in different positions.

15 In the accompanying drawings—

20 Figure 1 is a vertical sectional view through a window disclosing an embodiment of the invention, the sashes being shown tilted.

25 Figure 2 is a view similar to Figure 1 but showing the sashes closed.

Figure 3 is a sectional view through Figure 2 approximately on line 3—3.

30 Figure 4 is a side view of the lower sash and associated parts taken on line 4—4 of Figure 3, a portion thereof being broken away for illustrating one of the springs.

35 Figure 5 is an enlarged detailed sectional view through Figure 1 on line 5—5.

Referring to the accompanying drawings, 1 indicates a frame of any desired kind as for instance wood, and to this frame is secured by screws or other means a plurality of pairs of guideways 2, there being shown in the drawings, and particularly in Figure 3, four of

40 these pairs of guideways, two pairs on each side whereby the respective sashes 3 and 4 may be readily accommodated and moved upwardly and downwardly in the usual manner of window sashes now in common use. These

45 sashes, if light, may be supported by suitable springs hereinafter fully described, but ordinarily they are counterbalanced by suitable weights, cables and pulleys 5. The weights, cables and pulleys 5 are of the usual construction and therefore need no addi-

tional description. As one sash and its associated guideways is identical with the other, the description of sash 3 will also apply to sash 4.

55 As illustrated particularly in Figure 3, sash 3 is provided with what may be termed a cam strip 6 on each end, the same having a depressed portion 7. This accommodates the outwardly pressed or cam portion 8 of the weather strip 9. This weather strip generally speaking is U-shaped in cross-section and the respective legs are each formed with a turned-over flange 10 which projects beneath the turned-over portion 11 of the guides 2. Springs 12 and 13 act continually on these flanges and on the base of the strips 2, for urging the weather strip 9 outwardly whereby it will resiliently press against the window sash. As illustrated in Figure 4, each of the respective springs are 60 welded as for instance at 14 to the flange 10 and resiliently press against the base of the guide way 2 whereby the flange may slide back and forth as the sash is raised or lowered. Ordinarily, the springs force the 65 weather strips 9 outwardly as shown in Figure 6 but when the sashes turn to the position shown in Figure 1, the springs are depressed and weather strips move inwardly as illustrated in Figure 5. Each weather strip is provided with a pair of pins 15 which are adapted to enter the respective apertures 16 when brought into proper alignment therewith. However, the pins 15 as shown in Figure 4, 70 are positioned slightly below these apertures when the window sash is resting against the window sill. It will therefore be necessary to raise the window first slightly as illustrated in Figure 1 in order to bring the pins into alignment. This will prevent any accidental swinging of the window sash when the window is closed.

75 When it is desired to wash the outside of the window or desired to rotate the window for any cause, the sash is raised as illustrated in Figure 1, and then swung to the desired angle. In swinging the window sash, the cam members and portions 7 and 8 will coact in such a manner that the respective window strips 9 will be depressed as shown in 80 85 90 95 100

Figure 5. This will produce a tension which will hold the sash 3 in any desired position.

As illustrated particularly in Figure 3, it will be seen that the sash 3 is pivotally supported by screws 17 and 18 loosely fitted in suitable apertures 19 and 20 but screwed into the respective nuts 21 which are preferably welded to the respective weather strips 9. The apertures 19 and 20 are preferably 10 slightly larger than the screws in order to permit the screws to move longitudinally inwardly as the cams 7 and 8 function during the turning movement of the sash 3. By providing a pivotal means as just set forth, the windows may be readily cleaned without reaching through the window frame and when in an ordinary position, may be slid up 15 and down in the usual manner without danger of rattling.

20. The spring pressed weather strip acts in the double capacity of means for preventing rattling and also as a weather strip and guide for the sash as it coacts with the pairs of guides 2.

25. I claim:

1. A window frame including a window sash, a metal strip on each edge of the window sash provided with a depressed cam portion extending longitudinally of the sash, a 30 weather strip coacting with each edge of the window sash, each of said weather strips being substantially U-shaped in cross-section and having the bottom of the U formed with a groove acting as a cam coacting with the 35 cam shaped portion on the metal strip adjacent thereto, each of said weather strips having a pair of laterally extending flanges, spring means carried by each of the weather strips for urging the same toward the window 40 sash and a guiding structure for each of the weather strips, each of said guiding structures having an inturned portion coacting with said laterally extending flanges for limiting the outward movement of the 45 weather strip.

2. A window including a sash, a weather strip arranged on each edge of the sash, means for pivotally connecting the sash with the respective weather strips, a pair of guides 50 for each weather strip, each of said guides having an in-turned flange and each weather strip having an out-turned flange extending beneath said in-turned flanges and spring means acting on the weather strips for urging 55 the flanges thereof toward said in-turned flanges whereby said window sash will be resiliently pinched between the respective weather strips, and frictionally held against rattling.

60. 3. A window including a pair of sashes, each sash having a metal strip extending from the top to the bottom thereof on each edge, each of said strips being depressed centrally, a weather strip coacting with said metal strips, each weather strip being sub-

stantially U-shaped in cross-section with the pressed out portion fitting into the depressed portion of the metal strip, pins for pivotally mounting the window sash on the weather strips, each of said weather strips having out-turned flanges and a pair of guides coacting with each weather strip, each of said guides having in-turned flanges for limiting the outward movement of said out-turned flanges, and a spring acting on each of said out-turned flanges for urging the weather strips toward the window sash.

4. A window including a window sash provided with a metal strip on each edge, each of said metal strips having a depressed end portion acting as a cam, a weather strip on each edge of said sash, each of said weather strips having pressed out cam portions fitting into the cam portions of said metal strips, a pin secured to each of said weather strips extending loosely through the metal strips and into the frame of the window sash for pivotally mounting the window sash on the weather strips, a pair of pins extending through each of said weather strips, a guide for each of said weather strips, each of said guides having a pair of notches spaced the same distance apart as said pins whereby when the pins are opposite said notches, said window sash may be rotated, and as it swings, said cams will function to force the weather strips outwardly away from the window sash, and spring means acting on each weather strip for resisting this outward movement whereby the window sash is held resiliently in any position to which it is moved.

5. A window including a sash, a weather strip on each edge of said sash, a pin secured to each of said weather strips extending into the frame of the window sash for pivotally mounting the window sash on the weather strips, a pair of pins extending through each of said weather strips, a guide for each of said weather strips, each of said guides having a pair of notches spaced the same distance apart as said pins whereby said pins are adapted to move through said notches and permit the window sash to be rotated on the first mentioned pins, and spring means on each of said weather strips for resiliently holding the sash in any position to which it is moved.
